UNITED STATES PATENT OFFICE.

SAMUEL B. VAN RANST, OF SYRACUSE, AND MORTON HAVENS, JR., OF ALBANY, NEW YORK; SAID VAN RANST ASSIGNOR TO CROUSE-HINDS COMPANY, OF SYRACUSE, NEW YORK, A CORPORATION OF NEW YORK.

ELECTRICAL APPLIANCE.

1,100,857.

Specification of Letters Patent. Patented June 23, 1914.

Application filed February 21, 1907. Serial No. 358,631.

To all whom it may concern:

Be it known that we, SAMUEL B. VAN RANST, of Syracuse, in the county of Onondaga and State of New York, and MORTON HAVENS, Jr., of Albany, in the county of Albany and State of New York, have invented a certain new and useful Electrical Appliance, of which the following is a specification.

10 This invention has for its object the production of a highly simple and efficient electrical appliance particularly suitable for use in conduit work; and it consists in the novel combinations and structures herein-after set forth and claimed.

15 In describing the invention, reference is had to the accompanying drawing in which like characters designate corresponding parts in all the views.

20 Figures 1 and 2 are, respectively, elevational and longitudinal sectional views of one construction of said invention. Fig. 3 is a plan view, partly in section, of the detached hollow body of this electrical appliance. Fig. 4 is a sectional view, on line A—A, Fig. 2. Fig. 5 is a view similar to Fig. 2 of another construction of the invention.

25 This electrical appliance comprises generally a hollow body 1, and a device 2 for the branching of electric circuits. As here illustrated the body 1 is elongated, and its internal chamber is of a width greater than the diameter of the conduit to be connected to said body for facilitating the necessary manipulation and connection of the circuit wires and minimizing the liability of short-circuiting within the electrical appliance. Said body 1 is also formed with a flattened 30 side 3 serving as a base, and with an opening 4 in the side 5 opposed to the base 3, such opening being of less size than the base. A raised part or post 6 projects from the inner face of the base 3, and is of a 35 height less than that of the opposing sides of the body 1, and greater than the diameter of the circuit wires 7 passed within the internal chamber of the body 1. Said raised part 6 may consist of a rib, as seen in Figs. 40 2 and 3, or of a cylindrical projection, as illustrated in Fig. 5, and is preferably spaced apart from the inner surfaces of opposing sides of the body 1, thus providing spaces 45 between such raised part and opposing sides

of the internal chamber of the body for 55 the reception of circuit wires.

Opposing sides of the body 1 arranged at an angle to the base 3 and the side 5 are formed with parts 8 diverging from the side 5, and the opposite parts of said opposing sides are provided with outwardly-projecting internally-threaded nipples 9, a portion 10 of each nipple being substantially alined with the flattened base 3, and the longitudinal openings or passages through the nipples 65 9 communicating with the spaces at opposite sides of the raised parts 6, and being arranged with their axes between, and unequally separated from, the upper and lower edges of the sides of the body provided with 70 the nipples 9. A conduit for electric wires is suitably connected to the body 1, said conduit preferably including tubular sections 11 arranged end to end and spaced apart, and screwing into the nipples 9 against shoulders 12 within the inner ends of the lengthwise passages of said nipples. It is thus apparent that opposing sides of the body 1 are provided with portions of reduced size and formed with openings respectively connected to the conduit and permitting the passage 75 of circuit wires continuously through the nipples 9 and the spaces at opposite sides of the raised part 6.

80 Preferably, the body 1 is provided with wire-engaging surfaces 13, Fig. 2, diverging from the inner portions of the lengthwise openings or passages of the nipples 9, at an angle to the axes of said nipples, and with additional internal wire-engaging surfaces 90 14, Fig. 3, diverging from parts of the inner portions of said openings interposed between the surfaces 13. As best seen in Fig. 2, two of the surfaces 13 diverge from the opening 4 toward the inner portions of the openings or passages of the nipples 9. Said diverging surfaces 13, 14 being arranged at an angle to the axes of the openings or passages of the nipples 9 facilitate bending of the circuit wires 7 within the hollow body 1 100 to connect said wires to the device 2 for the branching of electric circuits and also reduce to a minimum liability of the abrasion or injury of the outer insulating coatings of the wires 7.

105 The device 2 for the branching of electric circuits serves as a closure for the opening 4 and thereby forms a part of the inclosing

wall of the electric appliance and comprises terminals and a part of insulation which may be formed in two sections. In Figs. 1 and 2 such device is shown as adapted to receive an electric lamp, the outer portion or end of said device projecting above the side 5 and being provided with a socket extending inwardly from one end and containing the usual screw-shell 15 and central 10 terminal 16 for making contact with the terminals of the lamp. The middle portion of the device 2 substantially fits the opening 4, and the inner portion or end of said device is formed of less size than the opening 15 4, is movable through said opening into and out of the internal chamber of the hollow body 1, and is spaced apart from opposing inner surfaces of the body 1 for forming spaces at opposite sides of said portion or 20 end, opening into the spaces at opposite sides of the raised part or post 6, and thus communicating with the longitudinal openings or passages through the nipples 9, the inner end face 17 of said portion or end of the device 2 being mounted upon the raised part 6 and parts of said end face being spaced apart from the inner face of the base 3. Suitable means, as screws 18, movable through the outer surface of the middle portion of the device 2 and extending into the hollow body 1, serves to removably secure said device to the interior of the body 1 and preferably to the raised part or post 6. The portion or end of the device 2 within 35 the hollow body 1 is provided with terminals 19, 20 which extend into the spaces at opposite sides of said portion or end and are electrically connected to bared portions of the circuit wires 7, Fig. 4, and are suitably connected to the terminals 15, 16.

To those skilled in the art it will be understood that the device 2, instead of being in the form of a "receptacle" adapted to receive electric lamps, may be a "rosette" intended merely for the branching of electric wires. It will also be understood, as illustrated in Fig. 5, that said device for the branching of electric circuits may be provided with a shoulder 21 for engaging a rubber gasket 22 mounted on the edge surrounding the opening 4, and that said device may be composed of two parts 2^a and 2^b arranged one above the other and suitably connected together. When the device 2 is of said two-part construction, the terminals to which the wires 7 are connected, are elevated sufficiently to cause said wires to engage the surfaces 13, as shown in Fig. 5. In this construction the section, or part 2^b, is attached by a central screw to the wall 3, or stud 6, projecting from the same, and the section or part 2^a is held in place and connected to the section 2^b by screws 2^d.

What we claim is:

65 1. An electrical appliance for electric con-

duits, the same comprising a hollow body having one of its sides provided with an opening for connection to a conduit, said body being formed with an opening in another side arranged at an angle to the first-mentioned side, and the internal chamber of said body being formed of a width greater than the diameter of the conduit to be connected to the first-mentioned opening, and a device for the branching of electric circuits, said device having a portion thereof substantially fitting the last-mentioned opening, and having another portion thereof movable through said last-mentioned opening into and out of the internal chamber of the hollow body, opposing surfaces of said internal chamber and the last-mentioned portion of said device being spaced apart for forming wire receiving spaces at opposite sides of said last-mentioned portion communicating with the first-mentioned opening, and said device being provided with terminals for electrical connection to the circuit wires, the terminals being arranged in said spaces, substantially as and for the purpose specified.

2. In a device of the character specified, the combination of a hollow metallic body provided with an opening for the reception of a conduit, the opening being located in one wall thereof, a second opening of relatively large size provided in a side of the box extending at an angle to the wall formed with the first-mentioned opening, a cover for the larger opening, the cover being formed of insulating material, and electrically conducting circuit branching means held by the cover in operative relation with the wires or conductors passing into the chamber of the body, and fastening means for holding the cover and said branching means in position, the fastening means for the cover and branching means passing in a direction through the cover and the branching means and being accessible from the sides of the box formed with the larger opening, substantially as and for the purpose described.

3. In a device of the character specified, the combination of a hollow, integrally-formed body provided with an opening for the reception of a conduit, and like-wise provided with a second opening of relatively larger size, a seat projecting into the chamber formed within the body at a point below the edges of the walls which define the larger opening, and between side walls of the body, forming wire passages, a circuit-branching device adapted to close the second-mentioned opening, a portion of said circuit-branching device resting upon the afore-mentioned seat, and means for securing the circuit-branching device in position, substantially as and for the purpose set forth.

4. In a device of the character specified,

- the combination of a hollow, integrally-formed body provided with an opening for connection with a conduit and likewise provided with a second opening of relatively 5 larger size, a support projecting inwardly into the chamber in the body at a point below the edges of the walls which define the larger opening, the projection forming wire passages between opposite sides of the body 10 and the projection, a circuit-branching device provided with a portion adapted to rest upon said inwardly-projecting portion, the main body of the circuit-branching device being formed of insulating material and being 15 substantially coextensive with the larger opening, whereby it forms a closure for said opening, and means for securing said circuit-branching device in position upon the main body, substantially as and for the purpose specified. 20
5. An electric appliance for electric conduits, the same comprising an integral hollow metallic body having a side thereof provided with an opening for connection to a conduit, said body being formed with an opening of relatively larger size in a second side arranged at an angle to the first-mentioned side, and the internal chamber of said body being formed of a width greater 25 than the diameter of the conduit to be connected to the first-mentioned opening, and a device for the branching of electric circuits, the same comprising a main part of insulating material serving as a closure for 30 the second-mentioned opening and thereby forming part of the inclosing wall of the electrical appliance, said main part being movable from the contiguous portion of the inclosing wall of said body independently of 35 said contiguous portion, and terminals for electrical connection to the circuit wires, the terminals being carried by said main part, substantially as and for the purpose set forth. 40
45. 6. An electrical appliance for electric conduits, the same comprising a hollow metallic body having a side thereof provided with an opening in a second side arranged at an angle to the first-mentioned side, and a device for the branching of electric circuits, the same comprising a main part of insulating material serving as a closure for the second-mentioned opening and thereby forming part of the inclosing wall of the electrical appliance, said main part having a portion thereof formed of less size than the second-mentioned opening, and movable through 50 such opening into and out of the internal chamber of the hollow body, and having its inner end face supported on the side opposed to the second-mentioned opening, opposing surfaces of said portion and the 55 side supporting the same being spaced apart 60
- for forming wire-receiving spaces communicating with the first-mentioned opening, and said device being provided with terminals for electrical connection to the circuit wires, substantially as and for the purpose specified. 70
7. An electrical appliance for electric conduits, the same comprising a hollow body having a side thereof provided with an opening for connection to the conduit, said body being formed with an opening in a second side arranged at an angle to the first-mentioned side, and with a raised part on the inner face of the side opposed to the second side, the raised part being spaced apart from the inner surfaces of opposing sides of the body for forming wire-receiving spaces at opposite sides of said raised part communicating with the first-mentioned opening, and a device for the branching of electric circuits, such device serving as a closure for the second-mentioned opening and thereby forming part of the inclosing wall of the electrical appliance, and said device having a portion thereof formed of less size than the second-mentioned opening and movable through such opening into and out of the internal chamber of the hollow body and having its inner end face mounted on the raised part, and said device being provided with terminals for electrical connection to the circuit wires, substantially as and for the purpose described. 85
8. An electrical appliance for electric conduits, the same comprising a hollow body having a side thereof provided with an opening for connection to a conduit, said body being formed with an opening in a second side arranged at an angle to the first-mentioned side, a device for the branching of electric circuits, such device including a part of insulation serving as a closure for the second-mentioned opening and thereby forming part of the inclosing wall of the electrical appliance, and said device having a portion thereof movable through the second-mentioned opening into and out of the internal chamber of the hollow body, such portion of said device being provided with terminals for electrical connection to the circuit wires, and securing means extending through said device into the internal chamber of the hollow body for retaining said device in position, such securing means being exposed on the exterior of said device, substantially as and for the purpose described. 95
9. An electrical appliance for electric conduits, the same comprising an elongated hollow body formed with a flattened base and having its side opposed to the base formed with an opening of less size than said base, said body having a side arranged at substantially right angles to the base and having a part of its opposing side arranged 100
- 105
- 110
- 115
- 120
- 125
- 130

at an angle to the first-mentioned side, and the other part of said opposing side provided with a projecting internally-threaded nipple for connection to a conduit, a portion 5 of the nipple being substantially alined with the flattened base, and said body being also formed with a raised part on the inner face of the base, the raised part being of a height less than that of opposing sides of the body, 10 and being spaced apart from the inner surfaces of said opposing sides for forming wire-receiving spaces at opposite sides of such raised part communicating with the opening or passage through the nipple, and 15 the internal chamber of said body being formed of a width greater than the diameter of the conduit to be connected to the nipple, and a device for the branching of electric circuits, a portion of said device being 20 formed of less size than the opening in the side opposed to the base, and being movable through such opening into and out of the internal chamber of the hollow body and having its inner end face mounted on the raised 25 part, and said device being provided with terminals for electrical connection to the circuit wires, substantially as and for the purpose described.

10. An electrical appliance for electric 30 conduits, the same comprising a hollow metallic body having a side thereof provided with an opening for connection to a conduit, said body being formed with an opening in a second side arranged at an angle to 35 the first-mentioned side, a device for the branching of electric circuits, said device having a portion thereof substantially fitting the second-mentioned opening, and having another portion thereof movable through 40 such opening into and out of the internal chamber of the hollow body, opposing surfaces of said internal chamber and the last-mentioned portion of said device being spaced apart for forming wire-receiving 45 spaces at opposite sides of said last-mentioned portion communicating with the first-mentioned opening, and said device being provided with terminals for electrical connection to the circuit wires, the terminals being arranged in 50 said spaces, and screws movable through the outer surface of the portion of said device substantially fitting the second-mentioned opening, the screws extending into the hollow body and securing 55 said device to such body, substantially as and for the purpose specified.

11. An electrical appliance for electric 60 conduits, the same comprising an elongated hollow body formed with a flattened base and having its side opposed to the base formed with an opening of less size than said base, said body having a side arranged at substantially right angles to the base and having a part of its opposing side arranged 65 at an angle to the first-mentioned side, and

the opposite part of said opposing side provided with a projecting internally-threaded nipple for connection to a conduit, a portion of the nipple being substantially alined with the flattened base, and said body being also 70 formed with a raised part on the inner face of the base, the raised part being of a height less than that of opposing sides of the body, and being spaced apart from the inner surfaces of said opposing sides for forming 75 wire-receiving spaces at opposite sides of such raised part communicating with the opening or passage through the nipple, a device for the branching of electric circuits, said device having a portion thereof substantially fitting the second-mentioned opening, and having another portion thereof movable through such opening into and out of the internal chamber of the hollow body and having 80 its inner end face mounted on said raised part, opposing surfaces of said internal chamber and the last-mentioned portion of said device being spaced apart for forming wire-receiving spaces at opposite sides of 85 said last-mentioned portion communicating with the opening or passage of the nipple, and said device being provided with terminals for electrical connection to the circuit wires, the terminals being arranged in 90 said spaces, and screws movable through the outer surface of the portion of said device substantially fitting the second-mentioned opening, the screws extending into the hollow body and engaging the raised part for 95 securing said device to such body, substantially as and for the purpose set forth.

12. In a device of the character specified, the combination of a hollow integrally formed body portion, provided with an opening for connection with a conduit and with a second opening of a relatively larger size, a seat rising from the wall opposite the second opening and being of less width than the chamber within the body, in order to provide wire passages on opposite sides of such seat, a circuit branching device, the main body of which is formed of insulating material, said device being provided with an inwardly projecting portion which rests upon the seat, the inwardly projecting portion having wire terminals on opposite sides thereof projecting into the spaces on opposite sides of the seat, and said device being also provided with a section which overlies the upper edges of the walls around the second opening, and means for securing the circuit branching device in place, substantially as and for the purpose specified.

13. In a device of the character specified, the combination of a hollow body provided with an opening for connection with a conduit and with a second opening of relatively larger size, and a circuit branching device including a member mounted within the body and fixed to the wall thereof opposing 130

said opening, and a member closing the opening and detachably secured to the member within the body, the member closing the opening also extending into the body, substantially as and for the purpose described.

14. In a device of the character specified, the combination of a hollow, integrally-formed body portion provided with an opening for connection with a conduit and with a second opening of a relatively larger size, a seat within the chamber at a point below the edges of the walls which define the larger opening and above the wall opposite said larger opening and being spaced apart from opposing side walls on opposite sides of said opening, forming wire passages, a circuit branching device, the main body of which is formed of insulating material, said device being provided with an inwardly projecting member which rests upon the seat, and being likewise provided with a section which overlies the upper edges of the walls which define the larger opening, and means for securing said circuit branching device in place, said means coacting with the seat, substantially as and for the purpose set forth.

15. In a device of the character specified, the combination of a hollow body portion provided with an opening for connection with a conduit and with a second opening of a relatively larger size, a seat within the body at a point below the edges of the walls which define the larger opening, a circuit branching device, the main portion of which is formed of insulating material, said device including two separable members, one being mounted on the seat, and the other being mounted on the upper edges of the walls which define the larger opening, and serving as a closure for such opening, and means for holding said device in position, substantially as and for the purpose set forth.

16. In a device of the character specified and in combination, a hollow metallic body provided with an opening for connection to

a conduit, and with a second opening of relatively larger size, a circuit branching device including terminals and a member of insulation comprising two sections, one located within the chamber in the body and secured to the wall thereof opposing the second opening and the other closing said opening and having a part thereof overlying the marginal wall of the same and a part projecting into said opening and means coöperating with the first-named part for holding the second-named part in position, substantially as and for the purpose described.

17. In a device of the character specified and in combination, a hollow metallic body provided with an opening for connection to a conduit, and a second opening of relatively larger size, a circuit branching device including terminals and a member of insulation comprising two separable sections, one located in the chamber of the body and resting against the bottom wall thereof, the major portion of the opposing faces of said section and wall being spaced apart, a screw passing through the section and engaging the wall for holding the section in position, and the other section closing said opening and having a part depending within the same, and another part overlying the marginal wall thereof, and screws extending through the second section and coöperating with the first section for holding the second section in place, substantially as and for the purpose specified.

In testimony whereof, we have hereunto signed our names in the presence of two attesting witnesses, at Syracuse, in the county of Onondaga, in the State of New York, this 9th day of January, 1907.
